CLAIM

The ornamental design for a baby bouncer base, as shown and described.

DESCRIPTION

FIG. 1 is a top perspective view of a baby bouncer base, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of a collapsed configuration thereof;

FIG. 9 is a front view of the collapsed configuration thereof;

FIG. 10 is a rear view of the collapsed configuration thereof;

FIG. 11 is a left side view of the collapsed configuration thereof;

FIG. 12 is a right side view of the collapsed configuration thereof;

FIG. 13 is a top view of the collapsed configuration thereof; and,

FIG. 14 is a bottom view of the collapsed configuration thereof.

The broken lines in the drawings illustrate portions of the baby bouncer base that form no part of the claimed design.

1 Claim, 12 Drawing Sheets
